United States Patent Office

Des. 233,075
Patented Oct. 1, 1974

233,075

CHAIN SAW ENGINE CASING OR THE LIKE

Lloyd H. Tuggle, Shreveport, La., assignor to
Beaird-Poulan Inc., Shreveport, La.

Filed July 5, 1972, Ser. No. 269,113

Term of patent 14 years

Int. Cl. D15—01

U.S. Cl. D77—1 R

FIG. —

FIG. 2

FIG. 3

FIG. 4

FIG. 5

FIG. 1 is a side elevational view of the left hand side of a chain saw engine casing or the like embodying the design of the present invention;

FIG. 2 is a side view of the right hand side thereof;

FIG. 3 is a top view thereof;

FIG. 4 is a perspective view from the front left hand side thereof; and

FIG. 5 is a perspective view from the rear right hand side thereof.

I claim:

The ornamental design for a chain saw engine casing or the like, as shown and described.
